UNITED STATES PATENT OFFICE.

FREDERICK M. FURBER, OF REVERE, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING UPON SOLES.

1,111,791.

Specification of Letters Patent. Patented Sept. 29, 1914.

Application filed December 11, 1911. Serial No. 664,965.

To all whom it may concern:

Be it known that I, FREDERICK M. FURBER, a citizen of the United States, residing at Revere, in the county of Suffolk and State of Massachusetts, have invented certain improvements in Machines for Operating Upon Soles, of which the following description, in connection with the accompanying drawings, is a specification, like reference characters on the drawings indicating like parts in the several figures.

The present invention relates to machines for manufacturing boots and shoes and is herein illustrated in connection with a machine for cutting off the ends of a mock welt. In some classes of McKay work it is customary, in order to improve the appearance of the finished shoe, to attach a mock welt to the out-sole; and it is essential, in order 20 to produce a satisfactory joint between the in-sole and the mock welt, that the ends of said welt be alined and beveled, this operation being known as "welt butting."

The general object of this invention is to produce a machine which is capable of operating upon a welt or similar piece of stock in the manner indicated above and to this end one feature of the invention consists in the provision in a machine of the 30 class described of a bed for supporting a piece of stock, a knife, and means for causing relative movement between said knife and bed first to bring the knife above the stock and then to cause the knife to shave off a portion of the stock. In the illustrative machine the knife carrier is movable, the knife being moved back-foremost over the stock and then edge-foremost to perform the cutting operation.

40 In attaching the welt, which is commonly accomplished on a sewing or tacking machine, no careful attention is given to the location of the ends of the attached welt. As a result these ends commonly extend on 45 to the heel seat of the sole, are free and may curl up slightly from the face of the sole. Moreover, the point at which the stitches, or other series of fastening means, begins on one side is not properly alined with the 50 point at which the series ends on the other side. It is thus desirable that the fastening means be cut for a predetermined distance prior to the severing or butting of the welt by the knife and that this cutting be performed in such a manner that the ends of the

welt remain attached to the sole at points which are properly alined.

Accordingly, another feature of the invention consists in the provision in a machine of the class described of a support for 60 a piece of stock having a second piece fastened thereto, a fastening cutter, means for producing relative movement between said cutter and support to cause the cutter and support to be moved relatively longitudinally of the piece to disconnect the end of one piece, and means for severing the disconnected end. In the illustrative machine motion is imparted to the fastening cutter which is forced between the ends of the welt 70 and the face of the sole on the forward stroke while on the rearward stroke the ends of the welt are severed by the welt butting knife.

It is desirable that the heel seat of the 75 sole be leveled or "fleshed" so as to leave at that portion of the sole nothing but good firm stock, and a further feature of the invention consists in the provision in a machine of the class described of a support for 80 a sole having a welt attached thereto and means for successively butting the welt and fleshing the heel seat of the sole. In the illustrative machine a gage or presser is provided which bears a fixed relation to the 85 knife during the fleshing operation and thereby determines the depth of the cut; and in order to promote compactness of the machine the fastening cutter, which has been referred to above, is constructed and arranged to serve also as this gage or presser. With this construction the combined fastening cutter and gage is forced on the forward stroke between the welt and the sole, and on the return stroke is held in fixed relation to the knife during the fleshing of 90 the heel seat of the sole.

These and other features of the invention including certain details of construction and combinations of parts will be described in 100 connection with an illustrative machine and pointed out in the appended claims.

Referring now to the accompanying drawings:—

Figure 1 is a plan of a machine in which 105 the present invention is embodied; Fig. 2 is a side elevation of the machine, the carriage being shown in dotted lines in one of its extreme positions; Fig. 3 is a longitudinal section of the forward portion of the 110

machine; and Fig. 4 is a perspective showing the appearance of the ends of the welt and the heel seat of the sole produced by the operation of the machine.

5 The machine comprises a base 1 having guides 3 upon which is slidably a carriage 5, said carriage serving to support among other parts a knife carrier 7. It is desirable that either the knife or the bed which supports the stock be capable of yielding, and in the illustrative machine there is provided a yielding bed comprising a base 9 having a plate 11 fast to its upper face and being supported by springs 13, said bed being guided in its movements by screw bolts 15. The plate 11 is held in place by screws 17 and is provided on its upper surface with a corrugated portion whereby the sole may be held firmly in place. The knife carrier 7 is pivotally supported by the carriage 5, said carrier comprising a sleeve fastened by pins 19 to a rock-shaft 21 which is rotatably mounted in bearings in the carriage.

It is essential that relative movement be caused to take place between the knife and the stock supporting bed, and in the machine shown the knife carrier is reciprocated by means of a connecting-rod 23 pivoted at 25 to a rotatable segment 27. This segment is driven through suitable gearing from a shaft 29 provided with fast and loose pulleys 31 and 33 and is so controlled by suitable clutch and gear mechanism that upon depression of a treadle, which is attached to the cord 34, (see Fig. 3), the segment will be caused to make a complete revolution and come to rest. The clutch and gear mechanism will not be described in detail since any suitable mechanism of this type may be employed. It may be stated, however, that the mechanism which is outlined in the present application is shown and described in detail in my co-pending application Ser. No. 465,626. The pivot 25 may be adjusted along and clamped in any desired position in the channel 35, said channel being struck about the axis of rotation of the gear 37 as a center so that while the carriage 5 moves always in the same closed path, its initial position may be varied.

As will be explained presently, the knife carrier 7 in the operation of the machine rocks about the axis of the shaft 21. It is therefore necessary that the joint between the rod 23 and the carrier should be constructed so as to permit this rocking movement. Accordingly a block 39 which fits between the two downwardly extending flanges of the knife carrier 7 is pivotally mounted about an axis parallel to the axis of the shaft 21 by means of pivot screws 41 which pass through the said two flanges and are threaded into the block. The block is provided with a slot 43 to receive the end of the rod 23, and through this slotted por-

tion of the block and the end of the connecting-rod 23 passes a pivot pin 45. In order to permit the knife carrier to move angularly about the axis of the shaft 21 as well as to limit the extent of this movement, the heads of the pivot-screws 41 pass through comparatively large bores 47 in the upstanding flanges of the carriage 5. It will be understood that the downwardly extending flanges of the knife carrier fit between the upstanding flanges of the carriage 5.

If now a sole having a welt attached thereto is placed upon the bed and the segment 27 caused to make a revolution the welt-butting cutter herein shown as a knife 49 will first be raised and moved over the sole and then on the return movement will be brought down upon said sole so as to cut off the ends of the welt; and to prevent the knife from being brought too close to the bed, a stop 51 is provided on the knife carrier which co-operates with a stop 50 on the carriage 5. In order, however, to insure that the knife shall be rocked about the axis of the shaft 21 at the proper time and held in firm engagement with the stock during the return stroke, the following mechanism is provided: To one end of the shaft 21 there is fastened by a pin 52 an arm 53 which carries at its lower end a bearing member 55 for a rod 57, said rod having fast on its end a collar 59 provided with a socket to receive a stop-pin 61. This stop-pin is driven into the bearing member 55, and the socket of the collar is normally held in engagement with it by means of a coiled spring 63, having one end fast to a collar 65, which is rigid with the rod 57, and the other end fast to the bearing member 55, said spring being at all times under tension and tending to rotate the rod 57 in a clockwise direction as viewed in Fig. 1. With this construction the rod is normally held in the position shown in the drawings and tends to return to that position at all times.

Fast to the rear end of the rod 57 is a cam 67 having an inclined upper face which is arranged, when the carriage 5 is moved forward, to engage a roller 71 rotatably mounted upon a fixed stud 73, the action of the cam and roller being to depress the rear end of the rod 57 and thereby move the rock shaft 21 angularly to raise the knife carrier, said movement being resisted by a coiled spring 79 having one end fast to the knife carrier 7 and the other end fast to the sliding carriage 5. In order to release the knife carrier at the proper time so as to permit the knife to be forced into the stock, the cam 67 is provided with a tappet 75 with which a wiper 77 fast to the connecting-rod 23 co-operates to move the cam 67 angularly from beneath the roller 71. In Fig. 2 the rod 57 is shown in dotted lines at its forward position at the time at which the wiper 77 is about to en-

gage the tappet 75 and move the cam 67 from beneath the roller 71, it being understood that as the wiper 77 becomes disengaged from the tappet 75 and the sliding carriage moves backwardly the spring 63 will return the rod 57 to its normal angular position.

Disengagement between the wiper and tappet is arranged to take place after the carriage has started upon its return movement and while the knife carrier is approximately in the position shown in dotted lines in Fig. 3. It will be noted that the pull of the connecting rod on the return stroke of the carriage will tend to cause the knife to shear off the ends of the welt, and will supplement the action of spring 79 in returning the rod 57 to its normal position.

As has been explained above, it is desirable that the ends of the welt be disconnected from the sole for a certain distance and that means be provided for determining the amount of stock which is to be removed from the heel seat of the sole. Accordingly, there is mounted upon the carriage 5 a combined fastening cutter and gage 81 having a beveled edge, which is adapted to be forced beneath the ends of the welt, and a flat under face which serves to depress the sole and thereby limit and determine the depth to which the knife shall enter the heel seat. This will be clear from an examination of Fig. 3 wherein it will be seen that the edge of the knife 49, when the knife carrier is at the extreme limit of its left-hand movement, extends beyond and beneath the edge of the fastening cutter and gage 81. Although the members 81 and 49 have been referred to as a gage and a knife it will be apparent that together they form a pair of shears which open to receive the ends of the welt and close to shear off said ends.

The length of the cut produced depends on the location of the sole upon the bed; and if the under face of the knife is used as a stop, it will be evident that the initial position of said knife can be made to control the extent of the cut. The purpose of the segment 27 will now be clear, since by adjusting the pivot 25 along the channel 35, the carriage and with it the knife may be caused to start and come to rest in any desired position in the fixed path of the carriage.

The operation of the machine is as follows:—The pivot 25 is adjusted to the desired position and the sole is placed upon the bed with the edge of the heel in contact with the under side of the knife 49. The treadle is then depressed to cause the segment 27 to make a complete revolution. As the carriage moves forward the knife and gage ride up onto the heel of the sole 100 thereby depressing the bed against the force of the springs 13; and presently, when the cam 67 is forced beneath the roller 71, the knife is

raised to permit the ends of the welt 102 to pass between it and the gage 81, said gage being forced between the ends of the welt and the face of the sole to cut for a predetermined distance the stitches or other means by which the welt is attached. The relative position of the gage or fastening cutter and the knife at the end of the forward stroke of the carriage is shown in Fig. 3, the knife carrier being held from farther movement in a counter-clockwise direction by the ends of the screws 41 which are then in contact with the walls of the bores 47 in the carriage 5. As the carriage begins its return movement the wiper 77 strikes the tappet 75 thereby turning the rod 57 in opposition to the coiled springs 63 and releasing the cam 67 from engagement with the roller 71. The knife, under the combined action of the connecting rod 23 and the spring 79, is thereupon caused to coact with the gage 81 to shear off the ends of the welt; and during the farther return movement of the carriage the knife and gage are held in fixed relation with respect to each other the edge of the knife extending slightly below the under face of the gage. The effect of the whole operation of the machine is thus successively to "but" or cut off the ends of the welt and to "flesh" or even the heel seat, the finished product being shown in Fig. 4.

Although the invention has been set forth in connection with a particular machine, it should be understood that the invention is not limited in the scope of its application to the particular machine shown and described.

Having fully described my invention, what I claim as new and desire to secure by Letters Patent of the United States is:—

1. A machine of the class described having, in combination, a bed for supporting a piece of stock, a knife, yielding means for permitting relative movement in a given direction between said bed and knife, and means for causing relative movement in another direction between said knife and bed first to bring the knife above the stock and then to cause the knife to shave off a portion of the stock.

2. A machine of the class described having, in combination, a bed for supporting a piece of stock, a knife, yielding means for permitting relative movement between said bed and knife, and means for moving said knife back-foremost over said stock and then edge-foremost to shave off a portion of said stock.

3. A machine of the class described having, in combination, a bed for supporting a piece of stock, a knife located in front of said stock with its back presented toward said stock, and means for causing the knife to traverse the stock back foremost and then for reversing the direction of movement to cause the knife to enter the stock.

4. A machine of the class described having, in combination, a bed for supporting a piece of stock, springs arranged to permit the bed to yield, a knife arranged at an angle 5 to the surface of the bed and having its back toward said stock, the edge of the knife being located nearer to the surface of the bed than is the upper surface of the stock, and means for causing the stock to be traversed 10 by the knife first in a direction to cause the bed to yield and then in a direction to cause the knife to enter the stock.

5. A machine of the class described having, in combination, a bed for supporting a 15 piece of stock, a knife arranged at an angle to the surface of the bed and having its back toward said stock, the edge of the knife being located nearer to the surface of the bed than is the upper surface of the stock, 20 springs arranged to permit relative yielding movement between said knife and bed, and means for causing the stock to be traversed by the knife first in a direction to cause the bed to yield and then in a direction to cause 25 the knife to enter the stock.

6. A machine of the class described having, in combination, a support for a piece 30 of stock having a second piece fastened thereto, a fastening cutter, power actuated means for producing relative movement 35 between said cutter and support to cause said cutter to be forced between said pieces of stock to disconnect the end of one piece and similar means for severing the disconnected end.

7. A machine of the class described having, in combination, a support for a piece 40 of stock having a second piece fastened thereto, a fastening cutter, yielding means for permitting relative movement in a given direction between said support and cutter, means for producing relative movement in another direction between said support and cutter to cause said cutter to be forced 45 between said pieces of stock to disconnect the end of one piece, and means for severing the disconnected end.

8. A machine of the class described having, in combination, a support for a piece 50 of stock having a second piece fastened thereto, a fastening cutter, yielding means for permitting relative movement between said support and cutter, means for forcing said cutter between said pieces of stock to disconnect the end of one piece and means 55 for severing the disconnected end.

9. A machine of the class described having, in combination, a support for a sole having a welt fastened thereto, a fastening cutter, means for moving the fastening cutter in the direction of the length of the sole to force said cutter between the ends of the welt and the face of the sole and means for cutting off said ends.

10. A machine of the class described hav-

ing, in combination, a support for a sole having a welt fastened thereto, a fastening cutter, means for producing relative movement between said support and cutter longitudinally of said sole to cause the cutter to be forced between the ends of the welt and the face of the sole to disconnect the ends of the welt from the sole, a welt-butting knife, and means for causing said knife to sever the disconnected ends.

11. A machine of the class described having, in combination, a support for a sole having a welt fastened thereto, a carriage, a fastening cutter rigid with said carriage, a welt butting knife pivoted to said carriage, 70 means for producing relative movement between said support and carriage, means responsive to said relative movement for raising the knife to permit the fastening cutter to be forced between the ends of the welt and the face of the sole, and means for bringing the knife down upon said ends.

12. A machine of the class described having, in combination, a support for a sole having a welt fastened thereto, yielding means for sustaining said support, a carriage, a fastening cutter rigid therewith, a welt-butting knife pivoted thereon, means for producing relative movement between said support and carriage, means responsive 95 to said relative movement for raising the knife to permit the fastening cutter to be forced between the ends of the welt and the face of the sole, and means for bringing the knife down upon said ends.

13. A machine of the class described having, in combination, a support for a sole having a welt attached thereto, a knife, and means for moving said knife first in a path inclined to the plane of the sole and then in 105 a path parallel to said plane whereby the welt is butted and the heel seat fleshed in a single operation.

14. A machine of the class described having, in combination, a support for a sole 110 having a welt fastened thereto, springs for sustaining said support, a carriage, a combined fastening cutter and gage, and a knife mounted on said carriage, means for causing relative movement between said carriage and support whereby said knife and gage are pressed against said sole, means for raising the knife to permit the gage to be forced beneath the ends of the welt to support them, and means for causing the knife successively 115 to sever the ends so supported and to flesh the heel seat of the sole.

15. A machine of the class described having, in combination, a support for a sole having a welt fastened thereto, a carriage, a pair 125 of shears mounted on said carriage, means for producing relative movement between said carriage and support to cause said shears to approach the ends of said welt, means for opening said shears to permit the 130

ends of the welt to pass between them, and means for closing said shears to sever said ends.

16. A machine of the class described having, in combination, a support for a sole having a welt attached thereto, a pair of shears, means for producing relative movement between said support and shears to cause said shears to traverse the heel seat of said sole, means for opening said shears to permit the ends of the welt to pass between them, and means for closing said shears to sever the ends of the welt.

17. A machine of the class described having, in combination, a support for a sole having a welt attached thereto, a pair of shears, yielding means for permitting relative movement in a given direction between said shears and support, means for producing relative movement in another direction between said shears and support to cause said shears to traverse the heel seat of said sole, means for opening said shears to permit the ends of the welt to pass between them, and means for closing said shears to sever the ends of the welt.

18. A machine of the class described having, in combination, a support for a piece of stock having a second piece fastened thereto, a pair of shears, means for producing relative movement between said support and shears to cause said shears to press one of the pieces of stock down upon said support, means for separating the edges of the shears to permit the end of the other piece of stock to pass between them, and means for moving one member of said shears toward the other to shear off said end.

19. A machine of the class described, having, in combination, a support for a piece of stock having a second piece attached thereto, a pair of shears, yielding means for permitting relative movement in a given direction between said support and shears, means for producing relative movement in another direction between said support and shears to cause said shears to press one of the pieces of stock down upon said support, means for separating the edges of the shears to permit the end of the other piece of stock to pass between them, and means for moving one edge of said shears toward the other to shear off said end.

20. A machine of the class described having, in combination, a support for a sole hav-

ing a welt attached thereto, a welt butting cutter, said support and cutter being relatively movable, and means for causing said support and cutter to come to rest in different relative positions.

21. A machine of the class described having, in combination, a support for a piece of stock, a knife, means for causing relative movement between said knife and support, first to bring the knife over the stock and then to cause the knife to shave off a portion of the stock, and means for causing said support and knife to come to rest in different relative positions.

22. A machine of the class described having, in combination, a support for a sole having a welt attached thereto, means movable in a path of uniform length over said support and acting to sever the end of said welt, and means for varying the point at which said movable means starts and comes to rest.

23. A machine of the class described having, in combination, a bed for supporting a piece of stock, springs arranged to permit said bed to yield, a knife arranged at an angle to the surface of said bed and having its back toward said stock, the back of said knife serving as a gage or stop against which the edge of the stock is placed, and means for causing the stock to be traversed by the knife first in a direction to press the stock against the bed and then in a direction to cause the knife to enter the stock.

24. A machine of the class described having, in combination, a yielding bed for supporting a sole, a knife the plane of which is inclined to that of the bed, the cutting edge of said knife being located nearer to said bed than is the upper surface of said sole, means for causing relative movement between said bed and knife in a direction parallel to the plane of said bed to cause the edge of the knife to traverse a portion of the sole and thereby force the bed to yield, and means for reversing the direction of movement to cause the knife to shave off a portion of the sole.

In testimony whereof I have signed my name to this specification in the presence of two subscribing witnesses.

FREDERICK M. FURBER.
